William Mc Bright and James Mc Bright
Grist Mill Patent

This is to witness our true intent and meaning of the same con-
cerning a description in the words of the said William Mc Bright and James
Mc Bright, inventors of their improvement in the Grist Mill.

To all to whom these presents shall come. We it believe that we William
Mc Bright & James Mc Bright of the town of Unionville, Fairfield District
State of N. Carolina have invented a new & useful improvement in the grist
mill invented by Edward Newland of Quifford Co. State of N. Caro-
lina and patented by him in February 1837 & that the following is a full
exact description of the construction & operation of the machine as improved
by us. We claim as our improvement the increased length of the spindle, a
new mode of making the regulating bush. The spindle as improved by us is
as long as the spindle of the original patentia mill & the regulating bush by an
improvement is placed in the left hand frame at top, the bush below being only
screwing to keep the spindle stiff when in operation. The regulating bush above
is made of four pieces of metal or hard wood 3 inches long 3/8 by 3/8 of an
inch thick which is fixed in the left hand frame with an iron screw at the back
of each piece to tighten the bush up to the spindle when it turns. The bush below
is made of four pieces of hard wood similar long 3 by 1 1/2 inches thick let in
to the bush top (the end of the wood to the spindle) with a screw at the end of
each piece to bring the bush up to the spindle as it was an iron bolt with a
head through each piece with a long below to keep the pieces from shifting.
From this improvement the others are kept more easily parallel with each
other which is all important in grinding, the bushes are so completely fixed
that they seldom or never get out of order, in fact the mill is so completely
fixed in the frame that it is almost impossible to put it out of order. The above
described improvement we claim as our invention being calculated to make
the said mill more easily kept in order & expedite the grinding by keeping
the stones always parallel & steady.

Witnessed, John D. McCall
